DESIGN FOR A MAT LINK

Harold A. Weinstein, Providence, R. I.

Application February 4, 1941, Serial No. 98,723

Term of patent 7 years

To all whom it may concern:

Be it known that I, Harold A. Weinstein, a citizen of the United States, residing at Providence, in the county of Providence and State of Rhode Island, have invented a new, original, and ornamental Design for a Mat Link, of which the following is a specification, reference being had to the accompanying drawing, constituting a part thereof.

Fig. 1 is a plan view of mat link showing my new design; and

Fig. 2 is a side elevational view thereof.

I claim:

The ornamental design for a mat link, substantially as shown.

HAROLD A. WEINSTEIN.
